UNITED STATES PATENT OFFICE.

GRIFFIN S. ACKLEY, OF BROOKLYN, NEW YORK, ASSIGNOR TO G. S. ACKLEY & CO., A COPARTNERSHIP CONSISTING OF GRIFFIN S. ACKLEY AND HELEN T. ACKLEY.

BRAKE MECHANISM.

1,341,830.

Specification of Letters Patent.

Patented June 1, 1920.

Application filed April 24, 1919. Serial No. 292,277.

To all whom it may concern:

Be it known that I, GRIFFIN S. ACKLEY, a citizen of the United States, and resident of the city of New York, borough of Brooklyn, county of Kings, and State of New York, have invented certain new and useful Improvements in Brake Mechanisms, of which the following is a specification.

This invention relates to mechanism for controlling or operating brakes, more particularly car-brake mechanisms which are operated by means of a chain or the like wound on a suitable drum or other member.

The present invention is an improvement over those set forth in my previous Patents Nos. 1,022,561; 1,158,764 and 1,270,762; operating on the same general principles as the brake mechanisms shown in these patents.

20 The present invention has the same general objects of economy of space and ease of operation as those set forth in my previous patents and, in addition, to provide for operation of front and rear truck brakes 25 from the one mechanism and also to provide a novel means for shifting of the drum frame, as desired.

The construction by which these objects and others, which will be apparent from a 30 knowledge of the invention, are attained will be fully set forth in the following specification, taken in conjunction with the accompanying drawings, the various combinations and arrangements of parts constituting the present invention being more particularly set forth in the appended claims.

Figure 1 of the drawings is a horizontal sectional view of a brake operating mechanism illustrating one embodiment of my invention, this view being taken on the line 1—1 of Fig. 2.

Fig. 2 is a longitudinal axial section thereof.

Fig. 3 is a side elevation thereof, on a reduced scale, showing the car platform in vertical section.

Fig. 4 is an end elevation of Fig. 3.

Fig. 5 is a horizontal section on the line 5—5 of Fig. 3.

50 Fig. 6 is a detail sectional view showing a slightly modified form of brake staff.

Fig. 7 is a diagrammatic view showing the mechanism arranged to operate the front and rear truck brakes in unison.

55 In the drawings 1 indicates a portion of

the platform of a car of ordinary type. As here shown, my improved brake control mechanism comprises an open casting forming a supporting frame and adapted to be secured to the underside of the platform as 60 will be presently pointed out. This frame comprises an upper longitudinal bar 2 having at one end a depending cylindrical boss 3, a pair of arms 4 projecting downwardly and rearwardly from this boss, the boss being considered as at the front end of the frame.

These arms 4 curve inwardly toward one another and unite in a bearing member 5 which is disposed under the bar 2 and coöperates with the latter to provide a bearing for a winding drum, which is in its general construction similar to that described in my previous Patent No. 1,270,762 comprising a pair of spirally grooved cone sections 7 and 75 8 tapering outwardly from a central gear 9 which, in the present instance, is a spur gear. These sections have registering lugs 10 and 11 formed thereon to receive a bolt 12 whereby the chains 13 and 14 are secured 80 to the drum. The gear 9 may have an up-standing annular flange 15 near its periphery to keep the chain 13 clear of its teeth. This drum is suitably fixed on a vertical shaft 16 having at its upper end a head 17 85 located in a recess 18 in the upper side of the bar 2 and passing through suitable apertures in the bar 2 and the bearing 5 and having a collar 19 fixed on its lower end.

In the embodiment of the invention as 90 shown in Figs. 1 to 4, the chain 13 acts as the winding chain and is connected to the brake in the usual manner, while the chain 14 is fastened to the chain 13 and works in opposition thereto to function as a check 95 chain, the two chains being preferably of the same size so that in the event of breaking of the portion of chain 13, which winds on the drum, the check chain may be temporarily used as a winding chain.

The gear 9 meshes with a pinion 20, provided with a hub 21, which extends upwardly in the boss 3, the pinion being supported in the boss by means of a collar 22 secured by set screws 23 on the top of the hub 24 and resting in an enlarged recess 24 at the upper end of the opening through the boss, the collar 22 having a flange 25 which projects over the end of the hub 21 and the bottom part of collar 22 is pro- 110

vided with several openings to allow for the free lubricating of the roller bearing and hub.

The hub 21 is of smaller diameter than the opening through the boss 3 and antifriction rollers 26 are inserted therebetween, held in a cage 27 of usual construction, which rests on the top of pinion 20.

As a feature of the present invention I provide an improved means for mounting the casting or frame under the platform in a manner to permit of angular shifting of the position thereof as desired to give a direct pull from the drum to the brake beam. As here shown, the boss 3 has segmental flanges 30 formed on opposite sides thereof and which are provided with vertical slots 31 concentric to the pinion 20 to receive bolts 32 which are passed downwardly through the platform 1 and have nuts 33 threaded on their lower ends. The lower faces of the flanges may be formed with serrations 34 adapted to be engaged by similar serrations on washers 35 interposed between the nuts and the flanges 30. A third bolt 36 passes through the platform and through a suitable opening in the rear end of the bar 2 and has a nut 37 threaded on its lower end. Should it be desired to shift the casting a fresh hole is bored in the car platform at the desired point to accommodate the bolt 36 and the nuts 33 loosened to permit angular movement of the casting.

In the present instance, the bolts 32 pass through ears 38 on a plate 39 on the upper side of the car platform and which has a sleeve extension 40 projecting downwardly through the platform in axial alinement with the boss 3. Upon this sleeve 40 is freely mounted a ratchet wheel 41 having a hub 42 which extends downwardly into the sleeve; roller bearings 43, carried in a cage 44, being interposed between the sleeve and hub. The hubs 42 and 21 have square openings therethrough to receive the squared lower end 45 of a brake-staff 46 of usual form. A pawl 47, pivoted on a bolt 48 which passes through the plate 39 and through the platform 1, coöperates in the usual manner with the ratchet wheel 41.

In order to insure against any tendency of the pull of the brake chain causing any binding action between the hub 42 and sleeve 40 I provide a collar 49 which, at its upper end, fits snugly over the sleeve 40 and at its lower end fits snugly in the recess 24, thereby maintaining at all times a proper alinement of the sleeve 40 and boss 3.

In Fig. 6 I have shown the invention adapted for use in connection with a brake-staff 55 having an integral ratchet wheel 56. The portion 57 of the staff immediately below the ratchet wheel 56 is of equal diameter to the hub 42 and is inserted into the sleeve 40 with the rollers 43 therebetween.

The extreme lower portion 58 of the staff is square and is inserted into the hub 21 of the pinion 20, the construction being otherwise the same.

In Fig. 7 I have indicated diagrammatically the application of my device as a centrally located brake mechanism adapted to operate on the wheels of the front and rear trucks in unison. In this arrangement the check chain 14 is eliminated and a chain 60, which winds on the drum section, is provided, the chain extending in opposite directions and connecting to the brakes, indicated at 61 and 62, of the front and rear truck wheels. To cause the two chains to wind and unwind in unison the direction of winding of either chain on the drum 6 may be reversed, the chain 13 being here shown reversed, while a cross cut groove, such as indicated at 63 may lead from a point adjacent either or both of the lugs 10 and 11 to accommodate the chain.

The usual arrangement is to provide for the winding up of the chain by a right hand turning of the handle but in some cases it is desired to reverse this and provide for a left hand winding, which is usually done by changing the drum. With this construction it will be seen that the same drum can be used, as its construction provides for reversing the chain, thereby providing for the wind up with either a right or left hand turning of the same, in a very simple manner and without changing the drum.

It will also be noted that the winding faces of the drums are eccentric with reference to the axis, thereby providing for a decreasing speed of winding as the chain tightens.

What I claim is:—

1. In a brake mechanism, a frame comprising a top bar adapted to be secured to the platform of a car, a cylindrical boss depending from one end of said bar, a pair of curved arms extending downwardly and rearwardly from said boss and uniting to form a bearing, a winding drum carried by the said bar and bearing and having a fixed gear, said drum being adapted to have a brake chain attached thereto, and means carried by said boss for rotating said gear, said means comprising a pinion located at the lower end of the boss and having a hub projecting upwardly into said boss, a collar secured on the upper end of said hub, said collar being supported by said boss, said hub being adapted to receive a brake staff.

2. In a brake mechanism, a frame, a winding drum comprising a central horizontal gear, and tapering sections on each side thereof, said gear having an upstanding annular flange near its periphery, for the purpose set forth.

3. In a brake mechanism, a frame, a winding drum comprising a gear and a grooved

tapering chain receiving section, and means whereby a chain may be attached to said section adjacent its larger end, said section being formed with a cross-cut groove extending from a point adjacent said means whereby a chain may be wound in either direction upon the drum.

4. In a brake mechanism, a frame, a winding drum having a central gear and tapering grooved sections on opposite sides thereof, and means whereby a pair of chains may be secured to the respective sections, one of said sections being formed with a cross cut groove to permit of a chain being wound in either direction thereon.

5. In a brake mechanism, in combination with a car platform, a frame secured to said platform and having a cylindrical boss at one end, a geared drum upon the frame, a pinion for rotating said drum, said pinion having a hub projecting upwardly in the said boss, means supporting said hub from its upper end, a plate upon the car platform having a depending sleeve in axial alignment with said boss, a ratchet wheel upon said plate and having a hub extending downwardly into said sleeve, a collar surrounding said sleeve and projecting into said boss, a brake staff passing downward through said hubs, and a pawl mounted on said plate and adapted to engage said ratchet wheel.

6. In a brake mechanism, a frame, a winding drum comprising a central gear and tapering grooved sections on opposite sides thereof, and means whereby a pair of chains may be secured to the respective sections, one of said sections being formed to permit one of said chains to be wound thereon in a reverse direction from the other chain, said chains extending from said sections in opposite directions and adapted to be operatively connected to the brakes at opposite ends of the car and to operate the same in unison.

Signed at the city, county and State of New York, this 21st day of April, 1919.

GRiffin S. ACKLEY.
